UNITED STATES PATENT OFFICE

150,226

DESIGN FOR A LAWN MOWER HOUSING

Vern N. Haglund, Lakewood, Colo., assignor of one-third to Clarence J. Grenfell and one-third to Charles F. Meffley, both of Denver, Colo.

Application June 7, 1946, Serial No. 130,510

Term of patent 14 years

(Cl. D40—1)

To all whom it may concern:

Be it known that I, Vern N. Haglund, a citizen of the United States, residing at Lakewood, in the county of Jefferson, State of Colorado, have invented a new, original, and ornamental Design for a Lawn Mower Housing, of which the following is a specification, reference being had to the accompanying drawing, forming part thereof.

Figure 1 is a top view of a lawn mower housing, showing my new design;

Figure 2 is a side view of the lawn mower housing; and

Figure 3 is a front view of the lawn mower housing.

I claim:

The ornamental design for a lawn mower housing, as shown.

VERN N. HAGLUND.
